United States Patent Office

Des. 196,824
Patented Nov. 5, 1963

196,824

TRANSMISSION

Emil A. Nakfoor, Milton A. Kramer, and Ernest O. Sodich, Houston, Tex., assignors, by mesne assignments, to Gulf Kramer Corporation, Houston, Tex., a corporation of Delaware

Filed Mar. 26, 1962, Ser. No. 69,445

Term of patent 14 years

(Cl. D77—1)

Fig. 1

Fig. 2

Fig. 3

Fig. 4

FIG. 1 is a top plan view of a transmission showing our new design.

FIG. 2 is a front elevation of the transmission.

FIG. 3 is a side elevation of the transmission.

FIG. 4 is a rear elevation of the transmission.

FIG. 5 is a perspective view as seen from the top front of the transmission.

FIG. 6 is a perspective view as seen from the top rear of the transmission.

The side not shown is substantially the same as the side shown in FIG. 3.

The bottom is substantially flat and plain.

What we claim is:

The ornamental design for a transmission, substantially as shown and described.
